UNITED STATES PATENT OFFICE.

GEORGE JONES, OF CHICAGO, ILLINOIS.

SELF-FEEDING HEATER.

SPECIFICATION forming part of Letters Patent No. 359,678, dated March 22, 1887.

Application filed August 7, 1886. Serial No. 210,250. (No model.)

To all whom it may concern:

Be it known that I, GEORGE JONES, residing at Chicago, in the county of Cook and State of Illinois, and a citizen of the United States, 5 have invented a new and useful Improvement in Self-Feeding Heaters, of which the following is a full description, reference being had to the accompanying drawings, in which—

Figure 1 is a vertical section of the upper 10 end of a steam-heater with my improvement attached thereto. Fig. 2 is a detail, being a vertical section of my device with the cover and valve open. Fig. 3 is a side elevation showing my device with the cover and valve 15 closed. Fig. 4 is a view of the pin upon which the valve is located. Fig. 5 is a modification showing my device attached to a self-feeding stove. Fig. 6 is a plan of my device as attached to a stove.

20 The object of my invention is to provide an improved means of releasing the accumulated gas in the fuel-magazines of self-feeding heaters, and thus preventing its ignition or escape into the room when the magazine is opened to 25 replenish it with fuel. This object I accomplish by providing the heater or stove with an attachment having a passage for fuel, which can be closed both at the top and bottom, and having a gas-chamber outside thereof, from 30 which a pipe leads to a chimney, a damper being provided in the pipe which is automatically opened and closed by the opening and closing of the cover of the attachment, as illustrated in the drawings.

35 In the drawings, A represents the upper end of a steam-heater, a being the steam-chamber.

B is a fuel-magazine, which in use extends downward as far as required. Its upper end 40 is provided with a flange, b, which rests upon a shoulder at the top of the heater, as shown in Fig. 1.

C is my attachment, which is secured to the top of the heater by bolts c, only one of which 45 is shown in the drawings. These bolts c also serve the purpose of securing parts of the heater together. The attachment C is provided with a central passage, D, which opens into the top of the magazine B, the lower end 50 of the passage being somewhat smaller in diameter than the top of the magazine, leaving

a space, d, between the two. Outside of D and surrounding the same is a chamber, e, into which gas can pass from the magazine B.

f is a removable piece or stopper adapted 55 to close the lower end of the passage D, and it is provided with a handle.

g is a hinged cover at the top of the passage D.

h is a short piece of pipe communicating 60 with the chamber e and adapted to receive a pipe, which leads therefrom to a chimney.

i is a damper in the pipe h.

j is a standard projecting upward from the cover g. 65

k is a short rod provided, as shown, with a screw-thread at each end.

l are sockets into which the screw-threaded ends of the rod k pass. One of these sockets is pivoted to the projection j, and the other 70 is pivoted to the upper end of a lever, m, the lower end of which is connected with a rod, n, upon which the damper is placed, the rod n being pivoted, as usual, in the walls of the pipe.

As shown, the cover g is so hinged to C that 75 when the cover is opened a given distance its movement will be arrested by a stop, o.

The operation is as follows: When fuel is to be fed to the magazine B, the cover g is to be opened, and as it is opened the damper i 80 will also be opened and brought into the position shown in Fig. 2. Then any gas which may have accumulated in the chamber e and in the magazine can pass off to the chimney through h. Then the part f can be removed 85 and fuel be put into the magazine through the passage D without inconvenience or danger from gas.

In Figs. 5 and 6 my improvement is shown attached directly to the top of a stove, F, provided with a fuel-magazine, G. My attachment, as shown in these figures, is secured in place by means of bolts p, which pass through a flange, q, at the lower end, and also through a flange, r, upon the top of the magazine, and 95 through another flange, s, upon the inside of the stove-body. In these figures a cover, H, which corresponds with the cover g of Fig. 1, is pivoted to the top of the attachment and swings in a horizontal plane, and the position 100 of the damper in h is changed to correspond, and it is operated automatically by the bar or

lever *t*, as represented in Figs. 5 and 6. When the cover *H* is closed, the damper will be closed, and as the cover *H* is swung around the damper will be opened, *t* being provided with a slot 5 at one end, and being pivoted at one end to the stove-cover, and at the other being connected with the pin upon which the damper is located.

What I claim as new, and desire to secure 10 by Letters Patent, is—

In a self-feeding heater, the combination of the fuel-magazine *B*, the attachment *C*, located above the fuel-magazine, and provided with a central fuel-passage, *D*, having its lower end 15 of less diameter than the top of the fuel-maga-

zine, and a gas-chamber, *e*, surrounding said fuel-passage and communicating with the magazine, the pipe *h*, leading from the gas-chamber, a damper, *i*, located in said pipe, a cover for the fuel-passage attachment, and 20 connections between the damper and cover, whereby combustion will be prevented within the magazine when the same is closed, and the gas will be permitted to escape through pipe *h* when the magazine is opened, substantially 25 as described.

GEORGE JONES.
